UNITED STATES PATENT OFFICE.

JAMES T. TAYLOR, OF NORMANGEE, TEXAS.

BROOM.

1,357,913.

Specification of Letters Patent. Patented Nov. 2, 1920.

Application filed February 14, 1919. Serial No. 277,048.

To all whom it may concern:

Be it known that I, JAMES T. TAYLOR, a citizen of the United States, residing at Normangee, in the county of Leon and State 5 of Texas, have invented new and useful Improvements in Brooms, of which the following is a specification.

This invention relates to brooms and particularly to a broom head attachment, and 10 one object of the same is to provide means for securing a broom to a handle in such manner that the broom straw, fiber or other strand material, when worn, may be replaced or renewed by substantially similar straw, 15 or strand material with facility and convenience and thereby materially reduce the cost of brooms and at the same time produce a strong and relatively durable broom structure.

With these and other advantages in view 20 the invention consists in the construction and arrangement of the several parts which will be more fully hereinafter described and claimed, and illustrated in the accompanying drawing in preferred form.

In the drawing—

Figure 1 is an elevation of a broom with the attachment applied and broken away and shown in section in part and embodying 30 the features of the invention.

Fig. 2 is a transverse vertical section taken on line 2—2, Fig. 1.

Fig. 3 is a horizontal section taken on the line 3—3, Fig. 1.

Figs. 4, 5 and 6 are detail perspective views of parts of the improved attachment shown separated.

The numeral 5 designates a handle of the usual type and adapted, in accordance with 40 the features of the invention, to be repeatedly used. The improved attachment comprises two head inclosing members or sections 6 and 7 of box-like form, the member 7 being of slightly smaller dimensions 45 than the member 6 and adapted to fit into the latter. Each of the members 6 and 7 are of truncated triangle form, and each has an upper or head flange 8 and side flanges 9, the latter reducing in width toward the 50 lower wider end of each member where the effective clamping action of the two members takes place. Between the lower terminals of the flanges 9 the lower wider ends of the members 6 and 7 are fully open so as 55 to bring opposing flat surfaces of the members against opposite portions of the broom

straw or other material in a manner which will alter expense. All the parts of the attachment are constructed of sheet metal struck up in the shape specified and as light 60 as possible consistent with the requisite strength and durability required to provide for an effective attachment for holding broom material with such rigidity as to resist breakage under the usual stress imposed 65 upon a broom during sweeping and scrubbing operations. The member or box section 6 has a tubular socket 10 rising from the center of the head flange 8 thereof to receive the handle 5 which is secured therein 70 and both members 6 and 7 have reinforcing metal strips or straps 11 and 12 applied over the outer sides thereof close to the lower wider edges, said straps being bent over a portion of the side flanges 9 as at 13. These 75 strips or straps 11 and 12 are firmly secured to the members or sections 6 and 7 and are used to strengthen the members at the points where they are applied against bending or distortion of the said members at the parts 80 where the greatest clamping action is effected relatively to the broom material. The strips or straps 11 and 12 are also provided as a positive supporting means for nutted securing bolts 14 which are inserted 85 through openings 15 formed at intervals through the strips or straps 11 and 12 and the adjacent wider portions of the members or box sections 6 and 7, the bolts 14 extending across from one section to the other 90 with their heads 16 bearing against one strip or strap and the nuts 17 thereof against the other strip or strap as clearly shown by Figs. 2 and 3. The tubular socket 10 and the handle 5 are reinforced 95 by a removable brace 18 intermediately bent or struck out as at 19 to provide a tongue 20 which fits over the upper end portion of the member or section 7, this brace having openings 21 and 22 respectively formed in 100 the upper end and the tongue 20 thereof. The part of the brace 18 above the tongue 20 is given a convex-concavo form in cross section so that it will snugly fit against the tubular socket 10, and the latter has opposite aligned openings 23 formed therein to receive a securing bolt and nut 24 which is inserted through the opening 21 of the brace, 105 and through the said openings 23; and in the upper central or head portions of the members or sections 6 and 7 openings 25 are formed with which the opening 22 of the

brace is adapted to register to receive a nutted securing bolt 26, the latter bolt also acting to firmly unite and hold the upper portions of the members or sections in associated relation. When the brace 18 is applied it will be seen that it resists bending or breakage of the tubular socket 10 and also strengthens the upper portions of the members or sections 6 and 7.

10 The members or sections 6 and 7 and the brace 18 may be readily separated by detaching the bolts 15, 26 and 24, and the broom straw, fiber or other strand material is gathered in close or contracted relation and forced into place in the member or section 6 in such full quantity that the body of the broom will be ample for the purposes of sweeping or scrubbing or will be equal to the fullness of an ordinary broom. After the broom material has been applied to the member or section 6 the member or section 7 is applied thereover and forced into the said member of section 6, and the bolts 14 inserted through the openings 15 and secured, and finally the brace 18 is applied and secured by the bolts 24 and 26. When the members 6 and 7 are secured at their lower wider ends against the broom material they will set up a clamping action on the latter, the degree of such action depending upon the tightening of the bolts 14 through their nuts 17, and it will be understood that the bolts 14 are inserted between the fibers of the broom material. It will also be seen that the downward flare or divergence of the members 6 and 7 will provide for the usual flare or divergence of the broom body from the head to the lower end thereof. At any time when found necessary the broom material 40 may be renewed or replaced by detaching the brace 18 and the members 6 and 7 and after disposition of the new material in the section or member 6, the member 7 and the brace 18 may be reassembled, and by this means the improved attachment may be repeatedly used in positively holding or supporting broom material. The reduction of the side flanges 9 of the members 6 and 7 permit a closer movement of the lower wider 50 portions of the members toward each other during the clamping action set up by the

bolts 14 than would be permitted if said flanges were of equal width throughout their lengths, and by having the member 7 fitted into the member 6 the broom material 55 is positively inclosed and prevented from spreading at the sides.

It will be understood that the parts of the improved attachment may be varied in general dimensions and proportions to adapt 60 the same to different sizes of brooms, but under ordinary conditions they will be of a size commensurate with the standardized broom proportions. By the use of the improved attachment considerable saving will 65 result in that the same broom handle may be repeatedly used, and in the event that the said handle should become broken at any time it may be readily replaced without impairing the remaining parts of the improved 70 attachment.

What is claimed as new is—

A broom attachment of the class specified, consisting of two box-like clamping members both flaring from their upper ends and 75 both having angular side flanges tapering toward the lower ends of the members, the one member being materially smaller than the other and loosely and detachably fitted therein, the tapering side flanges permitting 80 a maximum clamping drawing action at the lower extremities of the members, one of said clamping members being provided with upwardly projecting handle-engaging means, fastening devices extending transversely through the lower diverged extremities of the members close to the lower edges 85 of the latter and adapted to extend through the broom to which the members are applied, and a single fastening removably inserted 90 through the centers of the upper portions of the members, the clamping contraction of the members being effected to a maximum extent at their lower extremities.

In testimony whereof I have hereunto set 95 my hand in presence of two subscribing witnesses.

JAMES T. X TAYLOR.
